ELECTRIC WINCH CONTROL SYSTEM

Kurt Mahnke, Pittsburgh, Pa., and Earl B. Ankenman, Olathe, Kans., assignors to Westinghouse Electric Corporation, East Pittsburgh, Pa., a corporation of Pennsylvania

Application November 29, 1947, Serial No. 788,950

8 Claims. (Cl. 318—261)

1

Our invention relates to electric systems for controlling winches and, in particular, to control systems for operating the cargo winch booms of boom topping winches.

It is an object of our invention to devise a control system which permits the operator to raise and lower the boom merely by actuating the electric master control means, i. e., without necessitating the additional manipulation of a warping-drum handline, and which secures, under all operating conditions, a positive and reliable setting and release of the winch pawl without danger of shocks or overstress. Another object of the invention, in conjunction with the foregoing, is to safeguard the control system from causing pumping movements due to motor-stalling load conditions.

According to one feature of our invention, we provide an electric control system which, when set for lowering the boom, produces a limited hoisting motion in order to release the ratchet pawl of the winch before the lowering motion is started, and we equip this system with timing means which delay the setting of the pawl after lowering operations and first apply braking means which retard or stop the motor before the pawl is permitted to set.

According to still another feature of the invention, we equip the control system with an over-load relay and provide the latter with a lock-out coil which, when the relay has responded to over-load and has disconnected the motor from its energizing circuit, prevents the relay from falling out as long as the master control means are held in "run" position and thus prevents "pumping" which may otherwise occur under excessive, motor-stalling overload conditions.

These and other objects and features will be apparent from the following description of the embodiment of our invention exemplified in the drawing, in which:

Figure 1 shows a circuit diagram of an electric control system for a boom topping winch; while

Fig. 2 shows schematically the design principles of one of the contactors appertaining to the same system.

In Fig. 1 the boom structure of the winch is schematically illustrated at A. The structure has a tiltable winch boom 1. The boom cable is operated by a winch drum 2. The drum is equipped with locking means which comprise a ratchet gear 3 engageable by a ratchet pawl 4. The pawl must be released from gear 3 in order to permit lowering of the boom 1. The winch drum 2 is

2

further equipped with a spring-set friction brake 5. The appertaining magnetic control coil 6 must be energized in order to release the brake 5.

The winch drum 2 is connected to the armature 7 of a winch motor M by a mechanical transmission, here schematically represented by a broken line 8. The motor M has a shunt field winding 9 and a main field winding 10. Winding 10 is series connected with the armature 7 during hoisting operation and shunt-connected during lowering operation, as will be explained more in detail in a later place.

The motor M and the electric auxiliaries of the appertaining control system are energized from direct current mains 11 and 12 through a main switch 13. The energization of the motor is controlled by a hoisting contactor H and by a lowering contactor L of which only one is in picked-up condition at a time. The coil 14 of contactor H controls four contacts, denoted by 15 through 18, and is connected across mains 11 and 12 in series with a normally open contact 19. Contact 19 forms part of the master control means of the system. Contactor H has a lock-out coil 20 which is connected across the motor armature 7. The lock-out coil 20, even if energized, is ineffective after contactor H is picked up by coil 14. Coil 20 comes into effect only when it is sufficiently energized after contactor H has dropped out. Then the coil 20 secures a sufficient contact pressure at contact 16 and prevents the contactor from picking up as long as the then regenerative armature voltage remains above a given minimum value. In order to achieve this lock-out action, the contactor H, in its actual design, may have an armature of the type denoted by H' in Fig. 2. When the main coil 14, according to Fig. 2, is energized, it moves armature H' and closes contact 15 while opening contact 16. As a result, the air gap at coil 20 becomes so large that the subsequent energization of coil 20 has no effect on the armature. However, when thereafter coil 14 is deenergized and armature H' dropped back into the illustrated position, the energization of coil 20 holds contact 16 safely closed and locks the contactor in the dropped-off position. The lowering relay L has a control coil 21 for actuating two contacts 22 and 23. Coil 21 is energized under control by a normally open contact 24 which forms also part of the above-mentioned master control means. The circuit of coil 21 includes a pawl limit switch 25 of a ratchet control assembly S which has another limit switch 25'. Assembly S serves to release

the ratchet pawl 4 and is actuated by a solenoid 26.

The system is further equipped with an overload relay O whose contact 27 is controlled by an overload responsive control coil 27 disposed in the energizing circuit connections of the motor armature 7. Overload relay O has a lock-out coil 28 connected in parallel to the control coil 14 of hoist relay H. Coil 28 prevents relay O, when the latter is picked up, from dropping out as long as contact 19 is held closed by the operator.

The energizing circuit connections for motor M are controlled by a main contactor C whose control coil 29 actuates five contacts denoted by 30 through 34. The main contactor C has a lock-out coil 35 connected in parallel to the lock-out coil 20 of hoist contactor H across the motor armature 7. Coil 35 is ineffective relative to the movable armature structure of contactor C as long as the coil 29 is energized and holds the contactor in picked-up position. However, when the lock-out coil 35 is sufficiently energized while the contactor C is dropped off, it secures a sufficient contact pressure at contact 30 and prevents the coil 29 from moving the armature assembly. In this respect, the design and function of the double-coil contactor C is similar to the contactor H as explained above with reference to Fig. 2.

A timing relay T, which forms also part of the control system has a main control coil 36, a neutralizing coil 37 and two contacts 38 and 39. A short-circuited winding 40 in relay T provides the desired delay of the dropping out performance, and the delay period is also dependent upon the degree of excitation of the neutralizing coil 37.

Numerals 41 through 45 denote resistors. Resistor 43 is a starting resistor and serves to secure a desired acceleration of motor M. Resistor 44 permits adjusting the excitation of the neutralizing coil 37 in timing relay T and is connected with fixed resistor 45. Another resistor 46 is series connected with the brake release coil 6.

While the contacts 19 and 24, for the sake of convenience, are represented as pushbutton switches, it should be understood that these contacts may form part of a drum type master controller which is spring-biased to normally remain in the "off" position and can be held by the operator, against the spring bias, in either the hoist or the lowering position. Details of such a master controller or of other applicable types of master control means are not illustrated because their particular design is not essential to the invention proper, and the intended functions can be satisfactorily performed with the aid of the illustrated pushbutton contacts.

The system operates in the following manner: As long as main switch 13 is open, the hoist motor and all other elements of the system are deenergized, brake 5 is set to prevent drum 2 from revolving, and the drum is also locked by the ratchet pawl 4. In order to start the system, the operator closes main switch 13 and then closes contact 19 or 24, depending upon whether the winch boom is to be hoisted or lowered. The selected contact must be held closed as long as the hoisting or lowering performance is to continue, and the release of the contact has the effect of stopping the winch and resetting the system into deenergized and locked position.

More in detail, a hoisting performance involves the following operations. The closing of contact 19 has the effect of energizing coil 14 of hoisting

contactor H, lock-out coil 28 of overload relay O, and main coil 36 of timing relay T. Contactor H and relay T pick up. Contact 18 of contactor H and contact 39 of relay T close and energize coil 29 of main contactor C in the circuit

11-29-27-18-39-12, (1)

so that contactor C picks up. Contact 39 of relay T also energizes the solenoid 26 in the circuit

11-26-39-12. (2)

The neutralizing coil 37 of timing relay T is also energized through contact 39 in the circuit

11-31-45-39-12. (3)

Contacts 31 and 32 of main contactor C connect the motor M to the energizing mains, with resistor 43 series-connected to motor armature 7, in the circuit

11-31-15-43-19-7-17-27'-32-12. (4)

This energizing circuit includes the motor field winding 10 in series connection with the armature 7 so that the motor operates with a series characteristic.

The interlock contact 34 of the main contactor C bypasses the contact 39 of timing relay T and thus establishes for coil 29 of contactor C the holding circuit

11-29-27-18-34-12. (5)

Contact 33 of contactor C energizes the coil 6 so that brake 5 is released. Solenoid 26 actuates the assembly S thus closing limit switch 25 while opening limit switch 25' and releasing the pawl 4 from the drum ratchet 3. Consequently, the motor M now operates the winch drum 2 for lifting the boom 1. The limit switch 25' of assembly S opens the circuit of main coil 36 in timing relay T. Consequently, after a timed delay, relay T drops out and, at contact 38, connects the motor M to full line voltage in the circuit

11-31-38-19-7-17-27'-32-12. (6)

The desired accelerating period for motor M can be adjusted by displacing the sliding tap of resistor 44.

The motor stops when the operator releases contact 19 of the master switch. This causes all energized contactors to trip with the effect of resetting the system.

It will be recognized from the foregoing that the resistor 43 is inserted in the motor circuit only during the accelerating period, and that the illustrated example of a system according to our invention operates with only one accelerating step for the motor. If desired, however, two or more accelerating resistors and corresponding accelerating steps may be provided in accordance with well known practice and depending upon the requirements and desiderata of each particular application. The provision of more than one accelerating step requires, of course, the addition of one or more timing relays for securing the desired sequence of accelerating performance.

In order to lower the boom, the contact 24 is held by the operator in closed position. The closing of contact 24 causes the hoisting contactor H to pick up because its coil 14 is now energized in the circuit

11-14-25'-24-12. (7)

Lock-out coil 28 of relay O and main coil 36 of timing relay T are also energized in parallel connection to coil 14 of contactor H.

Timing relay T picks up and, at contact 39, energizes for coil 29 of contactor C, the above-mentioned circuit (1) so that contactor C picks up. Contact 39 also closes the above-mentioned circuit (2) for the solenoid coil 26 and the circuit (3) of the neutralizing coil 47 in timing relay T.

Contactor C now connects the motor M to the energizing mains by establishing the above-mentioned circuit (4). Consequently, although the master control means are set for lowering operation, the motor M is the first started in the hoisting direction with resistor 43 connected in series with the motor armature. The holding contact 34 in the above-mentioned circuit (5) maintains the contactor C in picked-up condition, and contact 33 energizes coil 6 to release the brake 5. The solenoid 26 releases the pawl 4, but the pawl limit switch 25' then deenergizes coil 14 of hoist contactor H, as well as the lock-out coil 28 of relay O. Contactor H drops out, and the pawl limit switch 25 now energizes coil 21 of the lowering contactor L in the circuit

11-21-25-24-12. (8)

The timing relay T remains energized through contact 24.

During the just-mentioned automatic transfer from hoist contactor H to lowering contactor L, the main contact C may momentarily drop out due to the switching-over of its coil circuit from contact 18 to contact 23, but the solenoid 26 of the pawl assembly S remains energized through contact 39 of timing relay T.

The motor is now connected as a shunt motor to prevent excessive lowering speeds. The energizing circuit now extends through

11-31-41-7-22-27'-32-12. (9)

The armature current limited by resistor 41 is now in opposite direction to the hoisting current. The circuit of main field winding 10, with resistors 42 and 43 inserted in series, is directly connected to the energizing mains with the same polarity as before in the circuit

11-31-42-43-10-22-27-32-12. (10)

The motor is stopped by permitting the contact 24 to return to its "off" position.

The motor field winding 9 is shunt-connected to the armature during hoisting as well as during lowering performance. It serves mainly as a speed limiting winding and may be omitted without otherwise affecting the operation of the system.

In order to prevent the pawl 4 from suddenly dropping into the ratchet gear 3 at the end of a lowering operation, the solenoid 26 of the assembly S is kept energized for a short additional interval of time by contact 39 of timing relay T, because relay T does not drop out immediately when being deenergized by the control contacts 24. The other contactors, however, drop out immediately and establish through armature 1, resistor 41, and series field winding 10, the dynamic braking circuit.

7-16-41-30-10-7. (11)

This braking circuit as well as the friction brake 5 are effective during the timing interval to stop the motor M before the pawl 4 is permitted to engage the ratchet gear 3. The lock-out coils 20 and 35 in contactors H and C, respectively, prevent the opening of the dynamic braking circuit (11) before the armature voltage of the motor M has been reduced sufficiently.

If during a hoisting performance an overload occurs, the coil 27' of relay O is sufficiently energized to open the contact 27. This has the effect of opening the coil circuit (1) of contactor C. As a result, the brake coil 6 is deenergized at contact 33, and the solenoid 26 is deenergized so that the brake is set and the pawl moved into locking engagement. However, in order to avoid the occurrence of pumping action under motor-stalling overloads, the relay O is held picked up by the lock-out coil 28 until the master contact 19 is released. This performance of lock-out coil 28 will be understood from the following:

When moderate overloads occur during the accelerating periods of the motor, while the motor is permitted to reach some speed and sufficient time is available for the accelerating relay T to drop out, no pumping effect can occur because the seal-in contact 34 of contactor C and the auxiliary contact 39 of relay T are then open. Consequently, when such moderate overloads cause tripping of the relay O, the contactor C is prevented from coming in again since the reclosing of contact 27 in relay O does not complete an energizing circuit for coil 29 of contactor C. If the overload relay O is set to pick up at an overload value above the initial starting peak that occurs during the normal acceleration of motor M, the overload relay O will not trip the contactor C even under stalled motor conditions before the end of the accelerating interval determined by the timing relay T. In order to obtain optimum operating conditions and satisfactory overload protection, however, the last-mentioned setting of the overload relay O is not recommendable. The overload relay O should be set to respond to a current value a little below the initial stalled current, i. e., the maximum current that may flow through the motor circuit under normal starting conditions before the starting resistor 43 has been shorted. There is a small delay of a fraction of a second in the action of the overload relay so that normally the starting peak current is reduced to below the setting of the relay if the motor accelerates. Hence, under normal conditions, the overload relay will not respond despite the fact that it is set for a current slightly below the initial stalled current. However, if the conditions are such that the motor is stalled during the accelerating period, then the relay O will respond and the conditions of the other relays in the system are then such that the overload relay and the contactor C may pick up and drop out alternately thus causing the above-mentioned undesirable pumping. Due to the lock-out action of coil 28, however, this possibility of pumping under excessive overloads is safely prevented and it is necessary to first release the master contact 19 before a new attempt of starting the motor is permitted.

During lowering performance, the decreased motor torque as well as the resistors in the motor energizing connections prevent the occurrence of excessive currents so that contact 37 of relay O will not open.

It will be understood from the foregoing by those skilled in the art that control systems according to the invention may be altered and modified as regards various circuit elements and interconnections and may be embodied by designs other than that specifically illustrated and described, without departing from the essence and features of the invention and within the scope of the claims annexed hereto.

We claim as our invention:

1. A winch control system, comprising winch locking means disposed for preventing lowering operation when set and having an electromagnetic releasing coil and limit switch means, a reversible winch motor, an energizing circuit for said motor, a hoist contactor for controlling said circuit to energize said motor for hoisting, a lowering contactor for controlling said circuit to energize said motor for lowering, master control means having selectively actuatable first and second contacts respectively, said first contact being connected with said hoist contactor to render the latter operative when said first contact is actuated, a timing relay having contact means connected with said contactors and having a control coil connected with said second contact and said releasing coil and said limit switch means so that, when said control coil is energized through said second contact, said hoist contactor is temporarily operated for an interval timed by said timing relay before said lowering contactor is operated.

2. A winch control system, comprising winch locking means disposed for preventing lowering operation when set and having an electromagnetic releasing coil, a reversible winch motor, control means for said motor having a hoist contactor and a lowering contactor for energizing, when operative, said motor to run in hoisting and lowering directions respectively, said control means including two selectively actuatable control contacts, one of said control contacts being connected to said hoist contactor for causing the latter to operate, a timing relay having a coil connected with said other control contact and having relay contacts connected with said two contactors so as to temporarily operate said hoist contactor and thereafter operate said lowering contactor when said other contact is actuated, and circuit means forming part of said control means and being connected to said releasing coil for releasing said locking means when either contactor is operative, said circuit means including a contact controlled by said timing relay so that, due to said latter contact, said locking means stays released during the change from operation of said hoist contactor to operation of said lowering contactor.

3. A winch control system, comprising winch locking means disposed for preventing lowering operation when set and having an electromagnetic releasing coil, a reversible winch motor having an armature and a field winding, energizing mains, control means disposed for connecting said motor to said mains and including a hoist contactor connecting, when operative, said armature and said field winding in series relation to each other across said mains for hoisting performance of said motor, said control means including a lowering contactor connecting, when operative, said armature and said field winding in parallel relation across said mains for lowering performance of said motor, said control means including selectively actuatable control contacts, one of said control contacts being connected to said hoist contactor for causing the latter to operate, and timing means associated with another one of said control contacts and with said two contactors so as to temporarily operate said hoist contactor and thereafter operate said lowering contactor when said other contact is actuated, said control means being connected with said releasing coil for releasing said locking means when either contactor is operative.

4. A winch control system, comprising winch locking means disposed for preventing lowering operation when set and having an electromagnetic releasing coil, a reversible winch motor, energizing circuit means for said motor, first control means disposed to connect, when actuated, said motor to said circuit means for hoisting, second control means disposed to connect, when actuated, said motor to said circuit means for lowering, winch braking means controlled by said second control means to brake said motor after actuation of said second control means, a timing relay controlled by said second control means and connected with said releasing coil for energizing the latter during actuation of said second control means and during an additional interval after said actuation of said second control means to secure braking of said motor before permitting said locking means to set.

5. A winch control system, comprising winch locking means disposed for preventing lowering operation when set and having an electromagnetic releasing coil, a reversible winch motor, energizing circuit means for said motor, first control means disposed to connect, when actuated, said motor to said circuit means for hoisting, second control means disposed to connect, when actuated, said motor to said circuit means for lowering, a timing relay controlled by said second control means to be picked up during actuation of said second control means and during an additional timed interval, said timing relay being connected with said releasing coil so as to maintain said locking means released during the pick-up period of said timing relay, and a dynamic braking resistor controlled by said first control means and said second control means to be effective across said motor only when said two control means are unactuated so that said motor is braked by said resistor during said additional interval before said timing relay permits said locking means to set.

6. A winch control system, comprising winch locking means disposed for preventing lowering operation when set and having an electromagnetic releasing coil, a reversible winch motor, energizing circuit means for said motor, selectively operable control means for connecting said motor to said circuit means for operation in hoisting and lowering directions respectively, said control means having a contact movable between "off" and "on" positions for operating said motor in hoisting direction when in said "on" position, a timing relay having a coil connected to said contact so as to pick up when said contact is moved to said "on" position and drop out upon elapse of a timing period after said contact is returned to said "off" position, braking means associated with said motor and controlled by said control means to brake said motor when said contact is moved from said "on" position to said "off" position, said releasing coil being connected to said control means and to said timing relay so as to be energized for releasing said locking means when said contact is moved to said "on" position and deenergized after elapse of said timing period to then permit said braking means to set, a load relay having a coil connected with said circuit means so as to pick-up when the motor energizing current exceeds a limit value and having a lock-out means for preventing said picked-up relay from dropping out as long as said contact is in said "on" position, said load relay having contact means electrically associated with said control means, and said timing relay for causing said mo-

tor to be braked and locked when said load relay is in picked up condition.

7. A control system for a winch with locking means for preventing lowering operation when set and an electromagnetic release coil for releasing said locking means, comprising a reversible winch motor, power supply leads, a hoist contactor and a lowering contactor of substantially immediate pick-up and drop-out performance, said contactors having respective contactor coils and having main contacts connecting said motor to said leads for hoisting and lowering respectively when said respective contactors are picked up, control means having two selectively actuatable control contacts of which one is connected with said hoist contactor coil, a timing relay of delayed drop-out performance having a relay contact and a relay coil, limit switch means actuatable by the release coil and movable between first and second positions corresponding to the set and released conditions respectively of the locking means, an energizing circuit controlled by said other control contact and being connected through said limit switch means with said hoist contactor coil and with said relay coil when said limit switch means is in said first position and with said lowering contactor coil when said limit switch means is in said second position, and a circuit for energizing said release coil having contact means connected with said respective contactors and being connected with said relay contact for releasing the winch locking means when any one of said contactors and relay is picked up.

8. A control system for a winch with locking means for preventing lowering when set and an electromagnetic release coil for releasing said locking means, comprising a reversible winch motor, a power circuit connected to said motor, a hoist contactor and a lowering contactor for controlling said circuit to run said motor in hoist-

ing and lowering directions respectively, a timing relay of delayed drop-out having a relay contact and a relay coil, an energizing circuit for the release coil connected with said relay contact to release the locking means when said timing relay is picked up, switch means controllable by said release coil and movable between a first position and a second position corresponding to the set and released conditions respectively of the locking means, operator-actuable control means having two selectively operable control contacts, one of said control contacts being connected with said hoist contactor and being also connected through said switch means with said timing relay for causing said timing relay to temporarily pick up when said motor starts running in the hoisting direction, a resistor connected in said power circuit and connected with said hoist contactor and said relay to be controlled thereby to be effective in said power circuit only when said hoist contactor and relay are both picked up, said other control contact being connected through said switch means with said hoist contactor in said first position of said switch means only and being connected through said switch means with said lowering contactor in said second position only, and said other control contact being also connected with said timing relay for causing it to remain picked up until after the actuation of said other control contact.
